(57) **CLAIM**

I claim the ornamental design for a plastic bag transporter, as shown and described.

DESCRIPTION

The present invention relates to a device for hanging and transporting plastic bags. The bags may be loaded onto the device of the present invention. The device may then be placed, for example, on a clothing hook of an automobile. FIG. 1 is an isometric view of a plastic bag transporter of the present invention.

FIG. 2 is a front view of the present invention.

FIG. 3 is a right view of the present invention.

FIG. 4 is a back view of the present invention.

FIG. 5 is a left view of the present invention.

FIG. 6 is a top view of the present invention; and,

FIG. 7 is a bottom view of the present invention.

The broken lines are for illustrative purposes only and form no part of the design of the present invention.
